(57) **CLAIM**

The ornamental design for a toothpaste carton, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a perspective view of a toothpaste carton;

FIG. 2 is a front view thereof;

FIG. 3 is a right side view thereof;

FIG. 4 is a back view thereof;

FIG. 5 is a left side view thereof;

FIG. 6 is a top view thereof; and

FIG. 7 is a bottom view thereof.

FIG. 8 is a perspective view of a toothpaste carton;

FIG. 9 is a front view thereof;

FIG. 10 is a right side view thereof;

FIG. 11 is a back view thereof;

FIG. 12 is a left side view thereof;

FIG. 13 is a top view thereof; and,

FIG. 14 is a bottom view thereof.

The broken lines shown in the drawings are for the purpose of illustrating parts of the article that form no part of the claimed design. The dot-dash broken lines shown in the drawings are for the purpose of illustrating a boundary that forms no part of the claimed design.

(Continued)

Crest^{TM} is a registered trademark from The Proctor and Gamble Company forming no part of the claimed design.
